SIGN CHARACTER ELEMENT

Harold R. Owen, Playa Del Rey, and Ralph Brown, Fall Brook, Calif., assignors to Electrical Products Corporation, Los Angeles, Calif., a corporation of California

Application December 20, 1948, Serial No. 66,376

3 Claims. (Cl. 40—130)

1

This invention relates to advertising and like signs and particularly to sign character elements for use in such signs and to a method of producing the same.

Advertising signs, particularly those of the electrically illuminated type, usually include a boxlike structure constructed from sheet metal and providing a background for painted or sheet metal sign character elements which are mounted thereon.

Such sign structures are subject to several disadvantages, one of which is that sheet metal supports of this character have little rigidity and must be adequately braced by a rigid internal structure. Even when such sign background structures are thus braced, they remain relatively flexible so that they bend readily when subjected to wind loads and this results in deformation and cracking or breaking of the paint or other coating material which is applied to the outer surfaces. Moreover, the sign character elements, being made from sheet metal, possess very little strength, are relatively expensive to manufacture, and possess little, if any, artistic appeal. It is thus seen that the majority of signs are custom built since their parts cannot be standardized, except where employed in identical signs.

We have discovered that a rigid sign structure is produced when it is composed of panels capable of being joined in end-to-end and side-by-side relationship, and when the panels are, in themselves, structural elements. Such a sign structure is disclosed in our application for patent for Sign Structure, Serial No. 25,328, filed May 6, 1948. As described in the application, the sign panels are made as cast metallic elements each having a platelike portion which provides a background, and perimetrical flanges, the latter components being adapted to be bolted or otherwise secured to the similar flanges of adjacent panels to provide, in effect, crossing ribs on the rear side of the sign structure which greatly strengthen the same and provide maximum rigidity. Signs composed of such structural and ornamental cast panels lend themselves to a large variety of shapes since the panels can be joined in many ways to produce signs of desired sizes and contours.

As will be apparent, sign panels of the cast type discussed above may assume various sizes and shapes and, in addition, may have raised or depressed sign character portions or letter strokes cast integral thereon or provided with sign character openings or windows therein

10 through which light can be transmitted so that any desirable effect can be readily produced.

The present invention is concerned with signs of the type last referred to above, that is, signs composed of a plurality of cast panels suitably joined. It has been determined that the cost of producing signs of this type can be maintained at a relatively low figure if the components, for example, the sign panels, are standardized as to size and shape. It has also been learned that if a sign panel can be made to serve either as an outline, silhouette or window type character element, the utility of such a panel would be increased and the over-all cost of the sign would be accordingly reduced.

15 It is, therefore, an important object of my invention to provide a sign panel of the cast metal type which is initially formed with a raised sign character portion or letter stroke which may, if desired, be outlined by a gaseous discharge illuminating tube. A related object is to provide a sign panel of the type referred to in which the raised letter stroke is of channel-shaped cross section and capable of being readily separated 20 from the platelike portion of the panel by a cutting operation, the cut being made in a plane which is parallel to the face of the panel. By this construction and separation of the raised sign character portion from the panel, a distinct sign character is produced which can be utilized 25 on the same or another sign by mounting it flat against a surface or on edge in upright position on a so-called sign deck. The panel from which the raised sign character is separated thus is provided with an opening or window of the same configuration as the separated character and through which light rays emanating from an electric illuminating source within the sign structure can be directed. It is thus apparent from 30 the above that the present invention contemplates the provision of a cast or molded composite sign panel which is capable of being readily divided to produce a pair of sign components so that by a single molding or casting process a pair of the components are at least partly formed and the over-all cost of the sign is materially reduced, this being an important object of the invention.

Another object is to provide a composite sign 35 element of the type specified in which the severed sign character component can be employed either by itself as an outline or silhouette letter or used in conjunction with the panel from which it is separated to produce various lighting effects.

40 A further object is to provide a method of

forming the separate sign character elements, the method consisting of a minimum number of extremely simple steps which can be carried out expeditiously and inexpensively.

Further objects of the invention will appear from the following specification and from the drawing, which is intended for the purpose of illustration only, and in which:

Fig. 1 is a perspective view of a composite sign character element embodying the features of the present invention;

Fig. 2 is a view similar to Fig. 1, showing a raised character portion or letter stroke separated from the main panel portion;

Fig. 3 is an enlarged sectional view, taken on a horizontal plane through the sign character element and showing the two companion parts employed in cooperative relationship to produce a silhouette lighting effect;

Fig. 4 is a perspective view of the sign panel from which the raised sign character element has been removed and illustrating a gaseous discharge illuminating tube disposed in the sign character opening or window thereof;

Fig. 5 is an enlarged sectional view, taken on line 5—5 of Fig. 4; and

Fig. 6 is an enlarged sectional view, taken on line 6—6 of Fig. 1.

The sign element 10 shown in Fig. 1 is generally similar to the sign panel disclosed in the pending application referred to previously and has a substantially flat, rectangular, platelike panel portion 11 and is provided with a perimetrical flange 12 projecting at right angles to the portion 11. The panel element 10, which is molded or cast from light-weight metal, is thus channel shape in cross section and, consequently, has relatively great strength and rigidity so that it is, in effect, a structural element. The flange 12 of the panel element 10 is provided with spaced apertures 13 which are adapted to register with the apertures of adjacent panel elements, bolts 14 or other fastening devices being inserted through the aligned apertures to secure the panels in end-to-end and side-by-side relationship. The flanges 12 thus provide, in effect, a network of crossing ribs which greatly strengthens and provides rigidity to the sign structure. While the exterior surface of the platelike panel portion 11 is herein shown as plain, that is, without ornamentation, it may be suitably embellished with ribs, grooves, raised squares or any other markings to enhance its appearance and to provide a mat surface capable of diffusing light projected thereagainst, as explained in the pending application.

The sign panel element 10 is provided with a sign character portion or letter stroke 15 which is cast integrally therewith and which projects forwardly from the platelike portion 11. The letter stroke 15 may be of any selected shape and size and, as shown in Figs. 1 and 6, is channel shape in cross section, being provided with side walls 16 and 17 and a front connecting web 18.

The sign panel element 10, having the sign character element 15 formed thereon, is applied to use as shown in Fig. 1. That is to say, when the element 10 is employed in an illuminated sign to designate a letter of a word for example, an electrically activated, gaseous discharge illuminating tube 20 may be mounted thereon as shown in Fig. 1 to provide an outline for the raised character 15, the ends of the tube extending inwardly through apertures in the panel portion 11 and provided with electrodes adapted for

connection to electrical contact means, the tube 20 being supported by suitable clips, these components being common in the art and, therefore, not shown or described herein.

As previously explained, it is sometimes desirable to employ sign character elements which have character openings in the form of windows through which light rays can project. The present invention contemplates the provision of such a sign character and, in accordance with the improved structure, this sign character is produced by the simple procedure of removing the raised sign character 15 from the panel 11 as shown in Fig. 2. The removal of the raised character portion 15 may be readily accomplished by the simple act of cutting it from the platelike portion 11 by means of a relatively thin rotary cutter or saw, the cut being made in a plane which is parallel to the face of the platelike portion 11. When the character portion 15 is removed, an opening or letter stroke 21, of the same size and contour as the raised character 15, is provided in the platelike panel portion 11. To apply the element 10 having the opening 21 to use, it may be incorporated in the sign structure by bolting its flange 12 to the corresponding flanges of adjacent panels, which may be plain or provided with other letter strokes. After the sign structure has been built up, an electrically activated, gaseous discharge tube 22, of the same size and contour as the opening 21, is mounted in the opening, the tube thus serving to produce the desired illuminated letter or other sign character. If desired, the letter stroke opening 21 may be closed by a translucent glass or plastic shield or window 25 through which the light rays emanating from the tube 22 are transmitted in a somewhat diffused condition, such an arrangement being shown in Figs. 4 and 5.

The sign character portion 15, after being separated from the composite sign panel 10, can be applied to use in the same or other signs in various ways. For example, the portion 15, which may be regarded as a letter stroke element, can be secured flat against any background and illuminated in any manner, or it can be mounted upon the top of a deck or other horizontal support to form a silhouette or shadow letter as disclosed in a pending application for patent on Deck Sign, Serial No. 39,240, filed by Harold R. Owen on July 17, 1948, now U. S. Patent No. 2,559,991, patented July 10, 1951. It is thus seen that the composite sign element 10, including the panel 11 and the letter stroke 15, can be used as shown in Fig. 1, and that upon separation of the letter stroke element 15 from the panel 11 these components can be employed in the same or in different signs for forming lettering having different lighting characteristics.

It is also within the concept of our invention to utilize the separated components 11 and 15 together as shown in Fig. 3 to produce a silhouette sign character. This result is accomplished by mounting the letter stroke element 15 forwardly of the panel element 11 and in alignment with the opening 21 thereof by means of suitable holders 29. An illuminating tube 30 is disposed within the letter stroke element 15 and follows the outline thereof. Since the element 15 is spaced from the forward surface of the panel 11, light emanating from the tube 30 is transmitted through the space between the elements and onto the surfaces of the panel element adjacent the edges of the opening 21. The projected light is reflected by the surfaces of the panel element, the

degree of reflectability of the panel element depending to a large extent upon the character of the reflecting surface. The effect of such lighting is to cause the letter stroke element to be sharply outlined against a lighted background and thus provide a silhouette or shadow letter. By varying the space between the two elements 11 and 15 and by changing the location of the illuminating tube 30 within the element 15, different lighting effects can be produced.

The present invention further contemplates a method of producing the sign character elements 11 and 15. As explained previously, the elements 11 and 15 comprise integral portions of a composite sign element 10 which is made from light weight sheet metal as a molding or casting. The composite element 10 is formed in a mold (not shown) which has a cavity of the size and outer shape of the element. The inner contour of the element 10 is defined by the companion part of the mold which provides, in effect, a core. To produce the sign elements 11 and 15, the molten metal is placed in the matrix portion of the mold and the core element forced thereagainst to cause the metal to flow and assume the shape of the composite element 10 which is thereafter removed from the mold, the molded product being of the shape disclosed in Figs. 1 and 6. The sign element 10 is then divided into the two components 11 and 15 by a simple cutting operation which may be performed in a machine or by means of a rotary saw or band saw around which the element may be passed by an operator. To separate the letter stroke element 15 from the panel 11, the latter is moved relative to the rotating saw in a plane which is parallel to the outer face of the panel and represented by the line x-x in Fig. 6, so as to sever the letter stroke close to the outer face of the panel. The two letter elements 11 and 15 are thus produced by a simple and economical method which consists merely of molding the composite sign element 10 and subsequently severing the raised letter stroke portion 15 from the panel portion. Preferably the outer surfaces of the sign elements 11 and 15 are coated with vitreous enamel or any other protective and ornamental coating and, as explained heretofore, these surfaces may be plain or marked with straight or crossing ribs or grooves or any desired geometrical designs to further enhance the appearance of the sign and provide backgrounds having various degrees of light reflectivity.

While we have herein disclosed the sign elements as embodied in preferred forms of construc-

tion and produced by a specific method, it will be apparent that various modifications therein may be made without departing from the spirit of the invention. Consequently, we do not wish to be limited in this respect, but desire to be afforded the full scope of the appended claims.

We claim as our invention:

1. A sign element, comprising: a cast, substantially planar panel having an opening representing a sign character in its face; a cast sign character member of the same configuration as said opening disposed forwardly of and in alignment with said opening in spaced relation to said face; and an electric gaseous discharge illuminating tube of the same configuration as said opening and disposed behind said sign character member and forwardly of said panel.

2. A sign element as defined in claim 1 in which said sign character member is substantially channel shaped in cross section and has a larger perimeter than said opening.

3. A sign element as defined in claim 1 in which said sign character member is substantially channel shaped in cross section and said tube is disposed within said member so as to transmit light onto the face of said panel to be reflected thereby.

HAROLD R. OWEN.
